UNITED STATES PATENT OFFICE.

REINHOLD D. SCHOENWETTER, OF BALTIMORE, MARYLAND, ASSIGNOR, BY MESNE ASSIGNMENTS, TO THE NATIONAL MANUFACTURING COMPANY, OF BALTIMORE, MARYLAND, A CORPORATION OF MARYLAND.

SHEET-FEEDING MACHINE.

1,416,985.

Specification of Letters Patent. Patented May 23, 1922.

Original application filed May 17, 1917, Serial No. 169,248. Divided and this application filed July 23, 1919. Serial No. 312,704.

To all whom it may concern:

Be it known that I, REINHOLD D. SCHOENWETTER, a citizen of the United States, residing at Baltimore, in the State of Maryland, have invented certain new and useful Improvements in Sheet-Feeding Machines; and I do hereby declare the following to be a full, clear, and exact description of the invention, such as will enable others skilled in the art to which it appertains to make and use the same.

My invention relates to sheet feeding machines.

This application is a division of my allowed application for Letters Patent, S. N. 169,248, filed May 17, 1917, for cigar banding machines.

More specifically, my invention relates to improvements in sheet feeding machines for use in cigar banding machines, in which a supply of cigar bands, each having a dry gummed end, is carried in a magazine. The cigar bands are stacked one upon another and delivered one at a time to the wetting mechanism and then to the band applying mechanism proper.

In such machines, it is of great importance that the bands be withdrawn from the magazine singly and not two or more at a time and that the band be delivered to the band applying mechanism in exactly the right position to be applied to the cigar.

In carrying out my invention, I make use of the instrumentalities illustrated in the accompanying drawings, in which:

Fig. 1 is a fragmentary plan view of my improved machine with parts omitted for the sake of clearness.

Fig. 2 is a vertical section partly in elevation of my improved machine.

Fig. 3 is a fragmentary elevation partly in section of the band magazine.

Fig. 4 is an enlarged detail perspective view of one of the band ejecting fingers.

Fig. 5 is an enlarged fragmentary detail section partly in elevation of the band magazine showing the ejecting fingers thrust inwardly to cause the bulging of the lowermost bands.

Fig. 6 is a detail vertical central section through one of the suction heads.

Fig. 7 is a top plan view of one of the cigar bands.

The machine as here shown comprises,

amongst other parts, a band magazine consisting of two upright vertically ribbed plates 1 and 2 mounted for horizontal adjustment by means of screws 3 and 4 and slots 5 and 6 upon portions of the frame of the machine, and each carrying upon its inner face two flanged vertically disposed guides 7, 8 and 9, 10, respectively, the said guides forming two vertical channels in which the cigar bands 11 are stacked as shown most clearly in Figs. 3 and 5.

The above-mentioned channels are open at their upper ends, but extending thereto at their bottoms are two rigid ledges 12 and 13, respectively, the upper faces of which are beveled so as to form two supporting surfaces converging towards each other. Normally, these ledges support the stack of bands in the magazine, the opposite ends of the lowermost band engaging said ledges at their bases, the forward ends or tips of the ledges being entirely free from the bands as shown most clearly in Fig. 3 and permitting of the free bulging of the lowermost band as shown in Fig. 5.

Each of the cigar bands in the case here illustrated is provided on one of its faces adjacent to one end with a coating 14 of gum arabic or other suitable adhesive which, as hereinbefore stated, is dry when the bands are placed in the magazine. The bands are stacked in the magazine, all with the gummed ends in the same direction and with their gummed faces up.

It has heretofore been found very difficult to withdraw the lowermost band from a stack of superposed bands carried in a magazine, with the assurance that the next band above will not follow. This difficulty is largely due to the weight of the bands which tends to cause those more immediately adjacent to the lower one to follow it when the latter is withdrawn.

The magazine which I here provide is designed to eliminate this weight of the bands on the lowermost one during the operation of withdrawing the band, and with this end in view, I have provided a magazine which is designed to cause the lowermost bands to bulge or extend outwardly from the stack and thereby not be subject to the effect above mentioned when being removed. Moreover, this method of operation separates the lowermost band from the one next above when,

for any reason, they have been stuck together.

For the purpose of effecting the above described bulging of the lowermost bands downward, I provide two tongues 16 and 17 fast, respectively, upon depending arms 18 and 19 of two bell crank levers pivotally mounted upon the uprights 1 and 2. These levers are provided, respectively, with arms 10 20 and 21, each of which is curved so as to follow the arc of a circle. These latter arms extend into openings in two arms 22 and 23 fast on a rock shaft 24.

For the purpose of imparting angular motion to this shaft, there is made fast thereto a depending arm 25, the lower end of which is flexibly connected through a link 25^a to a rocker arm 26 formed on a collar 26^a fast on a rock shaft 27. Also, fast on 20 this shaft is an arm 28 which connects through a link 29 to a lever 30 carrying a roller 31 which travels in a cam slot or groove 32 in one face of a disk 33 fast on a power shaft 34 which latter may be driven 25 from any desired source of power.

The inner faces of the tongues 16 and 17 are serrated and are backwardly sloping or beveled, as shown most clearly in Figs. 4 and 5. Shorter bands must be pressed from 30 the ends more than longer ones to produce the same bulging.

It will be seen that when uprights 1 and 2 are moved closer together, the effective horizontal parts of levers 20 and 21 shorten, 35 thus imparting a longer movement to the tongues 16 and 17. In this way, when uprights 1 and 2 are moved towards or away from each other, the same bulging is produced without requiring adjustment of position of levers 22 and 23.

The bands are actually withdrawn from the magazine by suction, for which purpose I have provided in the machine shown, amongst other parts, a suction head 35 45 rigidly mounted upon one end of the crooked metal tube 36 rigidly secured to a supporting frame 37 vertically slidably in guides 38 and adapted to receive vertical reciprocatory motion, for which purpose said frame 37 is 50 connected through a link 39 to a lever 40 carrying a roller 41 adapted to travel in an eccentric groove or slot 42 in one face of the disk 33. The lower end of the tube 36 is connected through a flexible tube 43 to the 55 forward end of one of the cylinders 44^a of a double air pump 44 driven from a disk 45 having an eccentric groove 46 therein in which travels a roller 47 carried by a lever 48 connected through a link 49 to the piston 60 cross head 50 of the air pump. The disk 45 is mounted upon a shaft 51 which receives its motion from power shaft 34 through sprocket gearing 34^a, 52 and 53. The suction head 35 is provided in its upper end with two 65 ports or air openings 54, 55, which commu-

nicate through a common passage 56 with the pipe 36. Inserted in the upper ends of these ports 54, 55 are two short rubber tubes or nipples 57 and 58 which extend slightly above the upper surface or face of the suction head.

The bands are removed from the magazine by the above described suction mechanism and are delivered to a conveyor which, in the machine here shown, comprises a pair of 75 metal belts 59 and 60 which are made to travel in the direction of their length in any approved manner. Fast on the conveyor belts 59 and 60, respectively, are a series of 80 spring clips 78 and 79 spaced at regular intervals thereon. The function of these clips is to remove the bands one at a time from the suction head 35 and hold them in position on the conveyor belts until they are removed therefrom and applied for any desired purpose.

The manner of driving the conveyor belts 59 and 60 and the use for which the bands delivered thereto from my improved sheet feeding machine are employed being no part 90 of my present invention are not herein further illustrated or described.

The operation of my improved sheet feeding machine is as follows:—

It will be assumed that shaft 34 is in rotation and continues so throughout a complete cycle of the machine. The continued rotation of the shaft 34 results through the movement imparting mechanism described, in the alternate movement of the tongues 16 100 and 17 towards and away from each other; an up and down movement of the suction head 35, and a reciprocating motion of the pump pistons.

At the beginning of the cycle, the tongues 105 16 and 17 are thrust inward, as shown in Fig. 5, causing the lowermost bands to bulge and the remainder of the stack of bands to be lifted, as shown. The tube 36 rises, thereby causing the suction head 35 to travel upward and bring the rubber nipples 57 and 58 thereon into engagement with the lowermost band, closing the suction head ports 54 and 55. At this instant, the piston of the pump 44^a starts on its outward stroke, thereby creating suction against the band in engagement with the suction head and holding it firmly thereon. After pausing with the suction head in the position described, the tube 36 travels downward causing the 110 suction head 35 to descend and carry with it the band held thereon by suction.

The suction head 35 continues its travel downward until it reaches the position indicated in Fig. 2 with the band held just above 115 the conveyor belts, said band being still held on the suction head by suction. The conveyor belts then advance, whereupon a pair of clips 78 and 79 engage the cigar band held by the suction head 35, remove it from said 120

suction head and carry it downward to any other part of the machine with which my improved sheet feeding machine is employed.

Immediately after the clips 78 and 79 engage the band, as just described, the pump piston reverses its stroke, thereby reversing the suction applied to the head 35. This operation can be then repeated indefinitely.

It should be understood that, while the expression "cigar band" is used, this is intended to include other strips or sheets of flexible material, the said expression being used merely for convenience.

I claim:

15 1. The combination with a magazine adapted to contain a stack of superposed cigar bands, of means acting endwise on said bands for bulging downward one or more bands adjacent to the bottom of the 20 stack to separate them from those above and for lifting the latter.

2. The combination with a magazine adapted to contain a stack of superposed cigar bands, of means acting periodically 25 and endwise on said bands for bulging downward one or more bands adjacent to the bottom of the stack to separate them from those above and for lifting the latter.

3. The combination with a magazine 30 adapted to contain a stack of superposed cigar bands, of means for bulging downward one or more bands adjacent to the bottom of the stack to separate them from those above, said band bulging means acting to simultaneously lift the stack of bands located above those which are bulged downward.

4. The combination with a magazine 40 adapted to contain a stack of superposed cigar bands, of means for bulging downward one or more of the bands adjacent to the bottom of the stack with arcs of different radii and for lifting the remaining bands.

5. The combination with a magazine 45 adapted to contain a stack of superposed cigar bands, of means for lifting the upper bands and for bulging downward one or more of the bands adjacent to the bottom of the stack with arcs of different radii, the lowermost band having the smallest radius.

50 6. The combination with a magazine adapted to contain a stack of superposed cigar bands, of means including a pair of movable tongues, and mechanism to cause said tongues to travel towards each other to exert pressure against opposite ends of the bands adjacent to the bottom of the stack to cause the latter to bulge downward and to lift the upper bands.

7. The combination with a magazine 60 having a pair of upright channels adapted to contain superposed cigar bands stacked therein and a downwardly beveled lip at the lower end of each of said channels adapted to normally support the stack of bands, 65 of a pair of movable tongues adapted to ex-

tend respectively into said channels above said lips, and mechanism to cause said tongues to alternately approach and recede from each other to cause the lowermost bands in the stack to alternately bulge and to straighten out and to lift the upper bands.

8. The combination with a magazine having means to support a stack of superposed cigar bands at their opposite ends, of means including a pair of movable tongues, and 75 means to cause the same to exert pressure against opposite ends of the bands adjacent to the bottom of the stack to cause the latter to bulge downward and to lift the upper bands.

9. The combination with a magazine having means to support a stack of superposed cigar bands at their opposite ends, of means including a pair of movable tongues having serrated faces, and means to cause said faces 85 of the tongues to exert pressure against opposite ends of the bands adjacent to the bottom of the stack to cause the latter to bulge downward and to lift the upper bands.

10. The combination with a magazine having means to support a stack of superposed cigar bands at their opposite ends, of means including a pair of movable tongues having 90 backwardly inclined band engaging faces, and means to cause the said faces of the 95 tongues to exert pressure against opposite ends of the bands adjacent to the bottom of the stack to cause the latter to bulge downward and to lift the upper bands.

11. The combination with a magazine having two upright channels adapted to contain a stack of superposed cigar bands and having stationary lips at the bottoms of said channels to normally support said bands at their opposite ends, a pair of movable 100 tongues adapted to travel transversely of said channels to engage opposite ends of said bands near the bottom of said channels, a pair of bell-crank levers on which the respective tongues are mounted, and 105 mechanism to operate said levers to cause said tongues to alternately travel towards and recede from each other.

12. The combination with a magazine having two upright channels adapted to contain 115 a stack of superposed cigar bands and having stationary lips at the bottoms of said channels to normally support said bands at their opposite ends, a pair of movable tongues adapted to travel transversely of 120 said channels to engage opposite ends of said bands near the bottom of said channels, a pair of bell-crank levers on which said tongues are respectively mounted, each of said levers having an arm curved to form 125 the arc of a circle, and a rocker arm individual to each of said curved arms and connected to said curved arms to permit the latter to be slid transversely of said rocker arms, and means for imparting motion to 130

said rocker arms to cause said tongues to alternately travel towards and recede from each other.

13. The combination with a magazine having a pair of upright channels adapted to contain a stack of superposed cigar bands, of means to adjust the horizontal distance between said channels, means acting on opposite ends of bands within said channels 10 to cause one or more bands at the lower end of the stack to bulge downward, and means to maintain the arcs of the bulged bands substantially constant for different adjustments of said channels without adjusting 15 the bulging means.

14. The combination with a magazine adapted to contain a stack of superposed cigar bands, of means adapted to lift the uppermost bands and exert pressure on the opposite ends of the lowermost band of the stack to cause one or more thereof to bulge downward, and suction means acting upon the lowermost bulged band of the stack to remove the same from the magazine.

15. The combination with a magazine adapted to contain a stack of superposed cigar bands, of periodically acting means adapted to lift the uppermost bands and exert pressure on the opposite ends of the lowermost band of the stack to cause one or more thereof to bulge downward, and periodically acting suction means acting upon the lowermost bulged band of the stack to remove the same from the magazine.

16. The combination with a magazine adapted to contain a stack of superposed

bands, of means for causing a partial separation of a band at the end of the stack from the adjacent band and for removing the weight of the uppermost band therefrom and means for subsequently removing said end band from the stack. 40

17. The combination with a magazine adapted to contain a stack of superposed bands, of means for causing the separation 45 of a portion of a band at the end of the stack from the adjacent band and for removing the weight of the uppermost band therefrom and means for subsequently engaging the separated portion for removing said end 50 band from the stack.

18. The combination with a magazine adapted to contain a stack of superposed bands, of means for bulging downward a portion of the lowermost band, and for removing the weight of the uppermost band therefrom, and means for subsequently engaging the bulged portion for removing 55 said lowermost band from the stack.

19. The combination with a magazine 60 adapted to contain a stack of superposed bands, of means for bulging downward a portion of the lowermost band, and for removing the weight of the uppermost band therefrom and pneumatic means for subsequently engaging the bulged portion for removing 65 said lowermost band from the stack.

In testimony whereof, I affix my signature.

REINHOLD D. SCHOENWETTER.
